UNITED STATES PATENT OFFICE.

VERNA E. DAVIDSON, OF DETROIT, MICHIGAN.

BURGLAR NET.

Application filed September 7, 1926. Serial No. 133,920.

My invention relates to a new and useful improvement in a burglar trap adapted for mounting in buildings such as banks, offices and the like, for the purpose of entrapping 5 burglars and for the purpose of protecting the occupants of the building or room, when locked in certain positions, from access by the undesired persons.

Another object of the invention is the provision in a device of this kind of a sectional telescoping closure for a door adapted for moving into position to cover the door opening when set into operation.

Another object of the invention is the provision in a device of this class of a sectional closure adapted for moving into position over a door opening and moving the door to closed position when set into operation.

Another object of the invention is the provision of a window grating adapted for moving over the window opening to close the same when set into operation.

Another object of the invention is the provision of an electrically operated catch for retaining the closures mentioned in inoperative condition under normal conditions.

Another object of the invention is the provision of a drum upon which the operating cord may be wound and unwound upon the 30 operation of the device.

Other objects will appear hereinafter.

The invention consists in the combination and arrangement of parts hereinafter described and claimed.

The invention will be best understood by a reference to the accompanying drawings which form a part of this specification and in which,

Fig. 1 is a fragmentary sectional view of 40 a room showing the invention applied with parts in side elevation, parts broken away and parts shown in section.

Fig. 2 is a front elevational view of the door opening closure.

Fig. 3 is a fragmentary sectional view 45 taken on substantially line 3—3 of Fig. 2.

Fig. 4 is a fragmentary side elevational view taken on substantially line 4—4 of Fig. 2.

Fig. 5 is a top plan view of the drum and operating motor.

Fig. 6 is a side elevational view of the invention taken on substantially line 6—6 of Fig. 5.

Fig. 7 is a side elevational view of a window opening showing the invention applied

thereto with parts broken away and parts shown in section.

Fig. 8 is a sectional view taken on substantially line 8—8 of Fig. 7.

Fig. 9 is a sectional view taken on substantially line 9—9 of Fig. 7.

Fig. 10 is a fragmentary sectional view taken on substantially line 10—10 of Fig. 7.

Fig. 11 is a fragmentary sectional view 65 showing the latch mechanism used at one side of the invention.

Fig. 12 is a fragmentary sectional view showing the latching mechanism in side elevation used at the other side of the invention. 70

As shown in Fig. 1 the invention is adapted for mounting in a building or similar room having a floor 17 and a ceiling 18, the floor being supported by suitable supports 19 and 20 to provide a basement below the floor.

The invention is illustrated as applied to a bank in which a transparent partition 21 will serve to enclose the teller or other clerk, having a mouth piece 22 mounted therein and provided with a suitable opening 23 having the closure 24, this partition and its parts being bullet proof. Extending along the one side of the building, beneath the ceiling 18, is a conduit 25, through which projects a cord 26 which is wound on the drum 27. This drum is driven by a motor 28, upon the shaft of which is mounted the gear 29 which meshes with the gear 30 carried by the bell crank 31, the gear 30 meshing with a similar gear 32 also carried by the bell crank 31. Mounted upon the shaft 33 of the drum 27 is a gear 34 with which the gear 32 may be brought into mesh at 80

will by rocking the bell crank 31 on its pivot 35 by means of the arm 36. Fixedly mounted upon the drum shaft 33 is a ratchet wheel 37 engaging with which is a rockingly mounted dog 38 normally held by the spring 39 in engagement with the teeth of the ratchet wheel 37. This dog 38 is electrically 85

operated by means of the coil 40 which is connected by the wires 41 to some suitable source of electrical energy. Upon an energizing of the coil 40, the dog 38 is rocked by the compressed spring 39 so as to disengage the ratchet wheel 37. The member 26 communicates with a trackage 38 which

projects over the door opening 39 formed in the wall of the building. A door 40 is 90 swingably mounted to serve as a closure for

Fig. 1 is a fragmentary sectional view of 95 a room showing the invention applied with parts in side elevation, parts broken away and parts shown in section.

Fig. 2 is a front elevational view of the door opening closure.

Fig. 3 is a fragmentary sectional view 100 taken on substantially line 3—3 of Fig. 2.

Fig. 4 is a fragmentary side elevational view taken on substantially line 4—4 of Fig. 2.

Fig. 5 is a top plan view of the drum and operating motor.

Fig. 6 is a side elevational view of the invention taken on substantially line 6—6 of Fig. 5.

Fig. 7 is a side elevational view of a window opening showing the invention applied

the opening 39 and the inner surface of the door 40 is provided adjacent its lower edge with an abutment 41 and adjacent its upper edge with an abutment 42. As shown in Fig. 4 this trackage embodies an iron top 43 having a side wall 44 turned inwardly to provide a bottom 45, and a side wall 46 turned inwardly to provide a bottom 47. A plurality of panels 48 are arranged in telescoping relation with each other, the edges being turned as shown in Fig. 3 and the upper end of each of these panels carries a roller 49 riding on the bottom portion 45 of the track. A roller 50 is mounted on the lower end of the panels 48 and rides in a track 51 mounted in the floor 17. A pulley 52 is mounted at the end of the horizontal trackage 38, a tube 53 projecting vertically downwardly through the floor and communicating with the housing 54 in which is positioned a weight 55. The cord 26 is attached to an eyelet 56 mounted in the weight 55 and a similar eyelet 57 at the other end of the weight is attached to the cord 59, this cord extending around the pulley 60 and wound on the drum 27. The cord 26 is secured to the end panel 48' which has the diagonal cut end 48'' as shown in Fig. 1.

The construction is such that upon a release of the dog 38 the weight 55 will serve to slide the panels 48 across the door opening 39, the panel 48' engaging the abutment members 41 and 42 and serving to move the door 40 to closed position and extend across the opening 39 to form an effective barrier against either entrance or exit. A diagonally extending beam 61 is provided with a slot 62 in which the edge of the panel 48' may engage so as to prevent tampering with a knife or other similar instrument to effect an opening of the sectional closure. A housing 63 is mounted behind the partition 21 and provided with the button switch 64 for the purpose of closing the circuit to the coil 40. The structure and arrangement is such that the operator when desired may close the switch 64 and thus effect a movement of the sectional closure across the door opening 69. A ratchet wheel 65 is mounted fixedly on the standard 66 and engage with a dog 67 mounted on the drum 27, so that backward rotation of the drum will be prevented.

I have also provided a closure for a window opening 68 in which may be positioned a window 69. Extending around the window opening 68 is a metallic frame 70 having its end 71 angularly turned as is likewise its end 72 to form side walls, the side walls 72 being again angularly turned as at 73 to form a track in which engages a roller 74. A similar structure is mounted at the opposite side of the window opening and a similar roller 74' engages in the track. A

partition 75 is mounted to prevent access to the space between the frame 70 and the partition 75. A tubular member 76 is mounted at each side of the window in the space thus formed and extending through this tubular member is a cord 77, one end of which is attached to the uppermost panel 78, this panel telescoping with the panel 79 which telescopes with the panel 80 etc. The lowermost panel is secured to the frame work provided.

Secured to the lower end of the cord 77 is a weight 81 riding in a guide 82 positioned below the floor 17. Mounted on the panel 78 is a projection 83 engageable with a latch 84 operated by the coil 85, this coil being connected by the wires 86 to a suitable source of electrical energy and through the switch 64. Upon a closing of the switch 64 the latch 84 will be withdrawn from operative position permitting the weights 81 to move the sections 78, 79 and 80 upwardly into position over the window opening, so as to effectively afford the protection desired.

A projection 87 is mounted on the panel 78 and serves to engage behind an electric latch 88 which is operated by the coil 89, this coil being suitably connected by the wires 90 to a source of electrical energy and through a switch.

The structure is such that when the weights 71 raise these sections upwardly the latch 88 will serve to lock the sections in operative position.

It is believed evident that the device constructed and arranged as I have set out is one which will afford effective protection for the purposes intended and one which is easily and quickly operated while at the same time simple in structure.

In order to rewind the cord so as to move the closures to inoperative position the latch 88 will be moved to inoperative position and the dog 67 moved to inoperative position upon which an operation of the motor 28 will effect through the gearing described a rewinding of the cords on the drum 27.

While I have illustrated and described the preferred form of my invention, I do not wish to limit myself to the precise form of structure shown, but desire to avail myself of such variations and modifications as may come within the scope of the appended claims.

Having thus described my invention what I claim as new and wish to secure by Letters Patent is:

1. A burglar trap of the class described adapted for use with a building having a door opening formed therein, comprising: a swingably mounted door for said opening; a sectional collapsible closure for said opening; a track extending across said opening above the upper edge thereof; a track extending across said opening below

the lower edge thereof; a roller mounted on the upper end of each of the sections of said closure engaging in the upper of said tracks; a roller on the lower end of each of said sections engaging in the lower track; means for moving said closure across said opening at will; means for preventing the reverse movement of said closure from across said door opening; and means on said door engageable with said closure for effecting a closing of said door upon movement of said closure across said opening and for limiting the opening movement of said door upon movement of said closure across said opening.

2. A burglar trap of the class described adapted for use with a building having a door opening formed therein, comprising: a swingably mounted door for said opening; a plurality of sections arranged in telescopic relation for forming a closure for said door opening; means operable for moving said sections to operative and inoperative position; and a pair of projections, one positioned adjacent the top and the other positioned adjacent the bottom and projecting outwardly from one face of said door, said projections being engageable by said sections upon movement of the same to operative position, and serving to swing said door to closed position, said projections engaging the face of said sections after movement of the same to operative position and preventing swinging of said swingable door; and groove bearing means for reception of the edge of the endmost of said sections upon movement of said sections to operative position for preventing lateral movement of the same.

4. A burglar trap of the class described adapted for use with a building having a door opening formed therein, comprising: a swingably mounted door for said opening; a sectional slid able closure for said opening, said closure being adapted for movement to operative or closing position upon swinging of said swingably mounted door to closing position; and means engageable with said closure upon incipient movement of the same to operative position for effecting the swinging of said swingably mounted door to closed position.

3. A burglar trap of the class described adapted for use with a building having a door opening formed therein, comprising: a

swingably mounted door for said opening; a plurality of sections arranged in telescopic relation for forming a closure for said door opening; means operable for moving said sections to operative and inoperative position; a pair of projections, one positioned adjacent the top and the other positioned adjacent the bottom and projecting outwardly from one face of said door, said projections being engageable by said sections upon movement of the same to operative position, and serving to swing said door to closed position, said projections engaging the face of said sections after movement of the same to operative position and preventing swinging of said swingable door; and groove bearing means for reception of the edge of the endmost of said sections upon movement of said sections to operative position for preventing lateral movement of the same.

In testimony whereof I have signed the foregoing.

VERNA E. DAVIDSON.
